UNITED STATES PATENT OFFICE.

MOSES SCHLATTER AND ELMER L. LIPP, OF LOS ANGELES, CALIFORNIA, ASSIGNEES,
BY MESNE ASSIGNMENTS, TO WILLIAMS BROS. AIRCRAFT CORPORATION, OF SAN
FRANCISCO, CALIFORNIA, A CORPORATION OF CALIFORNIA.

ACCELERATOR FOR INTERNAL-COMBUSTION ENGINES.

Application filed June 25, 1923. Serial No. 647,550.

This invention relates to means for opening and closing a throttle valve, and an object of the invention is to provide an appliance that is so constructed and arranged 5 that it can be attached to an engine and connected to a throttle lever by any person capable of operating cotted pin pliers and a screw driver, and which when connected to an engine and throttle lever will be highly 10 efficient to perform its function.

An object of the invention is to provide an appliance which, in addition to being easily attached to an engine and throttle lever, is also simple to operate, durable in 15 construction and neat in appearance.

An object of the invention is to provide an appliance that can be operated with either hand or foot, each independently of the other.

20 Other objects are long life and smooth operation and avoidance of severe strain upon the throttle mechanism.

Another object is to provide an appliance that is especially adapted for use 25 with the types of engine and carburetors installed in Ford cars; but we do not limit its use to engines of any particular type or make.

Another object is to provide an appliance 30 that can be easily attached to Ford engines already in use on cars irrespective of whether the floor boards of the car are or are not broken.

Another object is to so construct and combine the parts of the device, as an attachment, that when the same is installed, it will be stable, and the parts will be certain to maintain their operative relations.

The usual means employed in the Ford 40 car for operating the carburetor butterfly valve consists in a rod connected at one end to the said valve arm and at the other end to a rocker arm, which is fixed to the hand throttle control rod that is oscillated on its 45 axis by a hand lever, and this invention is broadly new, basic and pioneer in that we introduce in connection with the said valve and operating rod, a rack, a slideway and a toothed segment or sector and means 50 operable by a foot pedal and a spring to control the sector; the spring operating to normally hold the sector in position to lock the rack against longitudinal movement in the slideway; and the foot operated pedal

operating the sector to move the rack in the 55 slideway.

By this arrangement, when the foot pedal and its rack are held in normal position by the spring, the hand operated control rod operating through the slideway will move 60 both the slideway and the sector and will transmit motion to the said valve arm of the carburetor substantially the same as with the former connection between the rocker arm and the valve arm, and when the pedal 65 is operated, thus operating the rack, the valve arm will be operated by its connecting rod irrespective of the position of the hand-operated control rod.

An object of this invention is to utilize 70 the stock spring installed in Ford cars to support the hand operated throttle control rod; and this is effected by a flat strip of metal bent into the form of a U and embracing the control rod at such position as 75 to compress the spring by pressure from below, and said metal is pinched into frictional contact with the rod so as to maintain a greater tension on the spring than is customary with the spring when the Ford 80 machine is put out to the public.

By this arrangement the additional weight of the rack, the toothed segment and the slide, is supported; and the operative 85 positions of the parts is stably maintained.

Other objects, advantages and features of invention may appear from the accompanying drawing, the subjoined detail description and the appended claims.

The accompanying drawing illustrates 90 the invention.

Figure 1 is a plan view of an appliance constructed in accordance with this invention, and in place on an automobile, a portion 95 of which is shown.

Fig. 2 is a side elevation of the appliance as connected to a Ford automobile, the engine and other parts of which are indicated by dotted lines.

Fig. 3 is a fragmental edge view on a larger scale, of the slideway connected to the hand control rocker arm of a hand controlled carburetor throttle rod, a rack and a toothed segment, and also the carburetor 100 throttle operating rod.

Fig. 4 is a fragmental view showing in plan the appliance as attached to a Ford 105 automobile.

Fig. 5 is a fragmental plan view in section on line x^5 , Fig. 3.

Fig. 6 is a section on line x^6 , Fig. 5.

Fig. 7 is a detail of the compressed stabilizing spring and the clip compressed upon the hand-control rod, a fragment of which is shown.

Fig. 8 is a section on line x^8 , Fig. 7.

Fig. 9 is an enlarged detail of the universal joint connection between the segment rod and the pedal operated rock shaft.

The carbureter a and its throttle arm b are of common and well known construction and are not shown in detail.

15 The hand operated throttle control rod 1 is connected in the usual way with the hand throttle gasoline lever 2 as shown, and is provided in the usual way with a rocker arm 3 which is oscillated by said rod 1 and is

20 provided with a bearing 4 to which, in the ordinary construction heretofore, there has been attached a carbureter connecting rod, not shown in these drawings, but well known in the art.

25 5 indicates a journal pin working in the bearing 4 and held in said bearing by a cotter pin 6. Said journal pin 5 is connected to a slideway support 7 to which is fixed a rack housing and slideway composed of two angle irons, 8 and 9, spaced apart a distance equal to the thickness of the rack 10, and a toothed segment 11 which is in mesh with the segment and is pivoted by pivot 12 to the housing formed by the angle irons 8 and 9, and is connected by a rod 13 and a universal joint 14 with a crank 15 on a pedal rock shaft 16 that is journaled in the bearing 17 that is adapted to be attached to the engine, said bearing being carried by a mounting or bearing 18 fastened by screws 19 to the top 20 of the transmission case 21; said screws 19 taking the place of two of the usual screws for fastening such top on to the case.

40 45 The pedal 22 is fixed to the pedal rock shaft 16 and is adapted to rock said shaft and to thereby operate the connecting rod 13.

50 The crank arm 15 of the pedal shaft is connected by a spring 23 to the mounting 18 to normally hold the segment 11 and the pedal 22 retracted.

55 The universal joint 14 simply comprises a block having two holes 24 and 25 at right angles to each other; said holes forming a bearing for the crank end 26 of the crank arm 15, which end is in parallelism with the crank shaft 16. The hole 25 affords a bearing for the hook end 27 of the rod 13. Said hook end is bent at right angles to the main body of the rod 13 which is connected to the segment 11 by a second hook end 28.

60 65 In Figs. 2 and 7 the stabilizing spring 29 is shown compressed by a clip 30 which is simply a short piece of sheet metal bent

onto the rod 1 to take up and hold said spring at a tension sufficient to support the weight of the slideway and sector. Said clip 30 is made of U shape and the bend of the U is of the same radius as the rod 1; 70 and in applying the device, the spring is compressed away from the spring seat 31 on the rod and the U is inserted between the spring 29 and the spring seat 31 and thus compresses the spring to support the 75 rod with added tension to support the slideway and its adjuncts.

The sector is provided with end stops 33 and 34 adapted to abut against the rack bar 10 to limit the stroke of such bar so that 80 the force applied to the pedal will not apply excessive force to the throttle and will not jam or wrench the throttle mechanism.

In practice the operator may use either the hand lever or the pedal or may use both at 85 the same time without any interference one with the other.

We claim:

1. An accelerator comprising a foot lever; a bearing for said lever; a throttle lever; a floating housing; a rack bar in said housing; a rod having one end secured to said rack bar; an adjustable connection between the other end of said rod and said throttle lever; a sector pivotally mounted in said housing and arranged to engage and move said rack bar; a draw bar having one end pivotally connected to said sector; a pivotal connection between the other end of said draw bar and said foot lever; and a spring 100 for normally holding said foot lever in a predetermined position said spring having one end connected to said foot lever and the other end connected to said support.

2. An accelerator comprising a foot lever and a hand lever, said foot lever connected to an engine and said hand lever mounted on a steering post of an automobile; a throttle lever adapted to open and close a throttle valve in an engine carbureter; a floating 110 housing; a rack bar in said housing; a connection from said rack bar to said throttle lever; a sector in said housing arranged to engage and move said rack bar; a connection from said sector to said foot lever; and a connection from said floating housing to said hand lever.

3. An accelerator comprising a foot lever and a hand lever, said foot lever connected to an engine and said hand lever mounted on a steering post of an automobile; a throttle lever adapted to open and close a throttle valve in an engine carbureter; a floating housing; a rack bar in said housing; a connection from said rack bar to said throttle lever; a sector in said housing arranged to engage and move said rack bar; a connection from said sector to said foot lever; and a connection from said floating housing to said hand lever.

4. The combination with a carburetor throttle, a hand lever throttle rod and the usual spring for supporting such rod; of a rack slideway operably connected with the hand lever throttle rod; a throttle bar having a rack slideable in the slideway; means carried in the slideway and operable by the foot to operate the rack; and a clip adapted to be compressed around the hand lever 10 throttle rod and to increase the tension of the spring to hold the guideway and its load in operative position.
5. In a throttle control and in combination with a rack, a slideway therefor, a pedal, a connecting rod connecting between the pedal and slideway, and a spring to retract said rod and pedal; a sector operated by the connecting rod and adapted to operate the rack, and provided with stops to prevent excessive application of force to the throttle.

In testimony whereof, we have hereunto set our hands at Los Angeles, California, this 18th day of June, 1923.

MOSES SCHLATTER.
ELMER L. LIPP.
